UNITED STATES PATENT OFFICE.

KENJIRO OKAMURO, OF HONOLULU, TERRITORY OF HAWAII.

DESIGN FOR A HOOK.

55,483.

Specification for Design. Patented June 15, 1920.

Application filed June 6, 1919. Serial No. 302,354. Term of patent 14 years.

To all whom it may concern:

Be it known that I, KENJIRO OKAMURO, a subject of the Emperor of Japan, residing at 2524 Manoa, Honolulu, in the county of Honolulu and Territory of Hawaii, have invented a new, original, and ornamental Design for a Hook, of which the following is a specification, reference being had therein to the accompanying drawings.

Fig. 2 is a view in side elevation.

I claim:

The ornamental design for a hook as shown.

In testimony whereof I hereunto affix my signature.

KENJIRO OKAMURO.
